[57] CLAIM

The ornamental design for an arc layout device, as shown and described.

DESCRIPTION

FIG. 1 is a front, top and side perspective view of the arc layout device showing my new design;
FIG. 2 is a front elevational view thereof, the rear being a mirror image of the front shown in FIG. 2;
FIG. 3 is a side elevational view thereof;
FIG. 4 is a side elevational view thereof;
FIG. 5 is a top plan view thereof; and,
FIG. 6 is a bottom plan view thereof.

FIG. 1.

FIG. 3

FIG. 2

FIG. 4.

FIG. 6.

FIG. 5.
